CENTRIFUGAL MOTOR SPEED GOVERNOR
HAVING INERTIA EFFECTJames M. Naul, Fanwood, N. J., assignor to The
Singer Manufacturing Company, Elizabeth,
N. J., a corporation of New Jersey

Application September 2, 1943, Serial No. 500,900

7 claims. (Cl. 200—80)

This invention relates to speed governors for electric motors, and more particularly to that type of speed governor which operates, responsively to centrifugal force, to open the electric circuit to the motor when a predetermined speed has been attained and to close the circuit when the motor speed falls below that predetermined value.

While this type of speed governor is fairly satisfactory in maintaining constant predetermined speeds, there is, however, a certain amount of variation from the desired speeds, commonly known as "hunting," due to the inertia of the weights which form a part of the centrifugal governor. A speed governor of this type is disclosed in my United States Patent No. 2,293,996, Aug. 25, 1942.

The present invention has as a primary object to improve the speed governor disclosed in my prior patent by using the inertia effect of the weights to render the governor more sensitive to changes in speed, thereby to overcome the hunting tendency of the governor and more nearly to maintain the predetermined desired speeds.

This has been attained by so forming the support for the weights that in each change in speed the inertia of the weights reacts through the support to actuate the member which effects opening and closing of the motor circuit. This inertia force combines with the centrifugal force, generated by the rotation of the weights, thereby increasing the sensitivity of the governor to changes in speed.

It will be understood that the inertia force is effective instantaneously during a change of speed, whereas the centrifugal force is slower in its action and does not reach its full effect until a change of speed has been attained.

Like the governor disclosed in my prior patent, the present governor also includes manually controlled means for shifting the circuit-controlling switch contacts thereby to predetermine the speed of rotation of the motor. With the present improved governor that speed is obtained more quickly and is held more nearly constant than is possible with my prior governor which did not utilize the inertia of the weights.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the drawing,

Fig. 1 is a side elevation of an electric motor embodying the present invention, with certain parts thereof broken away, more clearly to disclose the improved motor speed governor.

Fig. 2 is a transverse section on the line 2—2 of Fig. 1.

Fig. 3 is a detail face view of the combined centrifugally and inertially actuated element of the speed governor.

Fig. 4 is a top view of the element shown in Fig. 3.

Fig. 5 is a diagrammatic view of the improved governor illustrating, in dotted lines, the action thereof under an inertia force, and

Fig. 6 is a diagrammatic illustration of a motor driving electric circuit embodying the present improved speed governor.

Referring more specifically to the drawing, the invention is disclosed as embodied in an electric motor M comprising a casing 1 which houses the usual field frame, field coils and other elements common to electric motors, including an armature shaft 2 which carries a pulley 3 adapted to drive any suitable mechanism. At one end, the motor casing is extended beyond its usual length, as indicated at 4, to form a housing for the improved governor, which is designated generally as G. The opposite side walls of the extension 4 are provided with openings 4' adapted to give access to the governor and these openings are normally closed by side cover-plates 5, as shown in Fig. 2. A resistor R and an arc-suppressing condenser C, illustrated in Fig. 6, are housed within a casing 6 secured to the upper side of the motor casing.

Before describing the improved speed governor, a brief description will be given of the motor-driving electric circuit in which the governor is embodied. This circuit is illustrated in Fig. 6 and comprises line wires 1 and 8 adapted to be connected together through the field coils 7', 8' of the motor M. Embodied in the line 7 is a line switch S comprising contacts 9 and 10 of which the latter is connected to the field coil 7' through the resistor R, across which is connected the arc-suppressing condenser C. When the line switch only is closed, current flows from the line 7 through the motor M, but in an amount insufficient to effect rotation of the motor, due to the action of the resistor R. Cooperating with the line switch S is a speed governor switch T comprising contacts 11 and 12 of which the former is connected to the contact 10 of the line switch 55 and the latter is connected with the field coil 7'

behind the resistor R. When both the line switch and the governor switch have been closed, full current flows from the line 1 to the motor without passing through the resistor, thereby tending to rotate the motor at full speed. When a predetermined speed has been attained, as determined by a setting of the contact 11, centrifugal and inertia forces acting on the governor G cause contacts 11 and 12 to be opened, whereupon current flows to the motor through the resistor, thereby causing the motor speed to be reduced. Deceleration of the motor causes the governor again to close the contacts 11 and 12 to effect acceleration of the motor. This continuous acceleration and deceleration of the motor tends to hold the motor speed at a substantially constant predetermined rate. Obviously, the more sensitive is the governor G the more nearly constant will the motor speed be maintained.

The contacts 9 and 10 of the line switch are preferably carried by spring-arms 13 and 14, respectively, secured, by screws 15, to the inner face of the end wall 16 of the motor housing extension 4. The arm 14 also carries the contact 11 of the governor switch, while the other contact, 12, of the governor switch is carried by a light spring-arm 17 secured to the end wall 16 by screws 18.

The line switch S and the governor switch T may be closed by any suitable mechanism, to cause the motor to run. One suitable means for this purpose is illustrated in the drawing, but it is to be understood that various other means are contemplated. As shown in the drawing, the switch-actuating means comprises a rod 19 slidably mounted in bearing-brackets 20 and 20' secured to the motor casing. Secured to one end of the rod 20, by nuts 21, 21^a, is an arm 22 of insulating material, the upper bifurcated end 22^a of which extends into the governor housing and straddles the contact-carrying arm 13. Surrounding the rod 19 between the bracket 20' and the nut 21, is a coil-spring 23 which tends to shift the rod 19, and, through the arm 22, the contact-carrying arm 13, to the right as seen in Fig. 1 thereby to open the line switch and to permit the governor switch to open under spring action. On the opposite end of the rod 19 is threaded a thumb-nut 24 which bears against the bearing-bracket 20 and serves, upon rotation, to shift the rod 19 and its switch-actuating arm 22 to the left, in opposition to the spring 23, to close the line and governor switches.

The improved governor preferably comprises two interconnected bowed springs b and d of which b is attached to a collar e secured upon the armature shaft 2 by set-screw f, while d is arranged diametrically of the shaft and serves as a switch operator. Spring b is of smaller radius than spring d. The springs b and d are secured together at their ends and carry, at their juncture, suitable weights 25 adapted to be moved outwardly under centrifugal force during rotation of the motor. At its mid-portion, in line with the axis of the shaft 2, the diametral spring d carries a button g of insulating material, adapted to act upon the contact arm 17, in opposition to the spring-tension of the latter, to control the opening and closing of the contacts 11 and 12 in the motor circuit.

As described in my above mentioned Patent No. 2,293,996, the unequal bowing of the elements b and d renders the governor more sensitive to variations in speed than prior governors of this type.

As hereinbefore stated, the primary object of

this invention is to provide a motor speed governor which is even more sensitive to variations in speed than that disclosed in my prior patent. This has been accomplished by utilizing the inertia of the weights 25 in conjunction with the centrifugal force generated by rotation of the weights. To that end, the oppositely extending arms of the bow spring b are twisted, as indicated at t, so that their outer ends, to which the weights 25 are attached, are arranged at an angle of approximately 60 degrees to the axis of rotation of the governor. Because of this angular arrangement of the arms of the bow spring b, variations in speed of rotation of the governor will, under the influence of the inertia of the weights 25, cause the outer ends of the spring arms to have a circumferential component of motion obliquely of a plane containing the axis of rotation of the governor and the weights 25. This circumferential component of motion will, through the flexing of the opposite ends of the bow spring b, be translated into a radial component, thereby straightening the bowed spring d and withdrawing the button g, when the speed is accelerated, thus opening the contacts of the switch T to reduce the speed of the motor, or, when the speed is decelerated, to further bow the spring d and effect closing of the contacts to increase the speed of the motor. For convenience, the bowed spring b may hereinafter be referred to as a supporting element and the spring d as a connecting element.

It will be understood that acceleration of the shaft 2 will, in opposition to the inertia of the weights 25, cause the arms of the spring b to be deflected outwardly and thereby reduce the speed of the motor, while, during deceleration of the shaft, the momentum of the weights will bend the arms of the supporting element inwardly and thus increase the speed of the motor. The inertia of the weights becomes effective instantaneously during a change of speed and works in conjunction with the slower acting centrifugal force of the weights thereby to render the governor more sensitive to variations in speed, whereby a more nearly uniform predetermined speed may be maintained.

Referring to Figs. 2, 3 and 5, let it be assumed that the shaft 2 and governor G are either at rest or are being rotated in the direction indicated by the arrows a. Now let it be assumed that the speed of rotation of the shaft is suddenly increased. The inertia of the weights 25 will act in the direction indicated by the arrows i and tend to hold the weights stationary or against acceleration. Thus, at that instant, there will be two opposed forces acting on the twisted arms of the bow spring b, one, the rotation of the shaft 2 which tends to turn the mid-portion of the spring b in the direction indicated by the arrows a, and the other, the inertia of the weights which opposes such rotation. These opposed forces, acting at radially spaced points on the twisted arms of the supporting element b cause the outer ends thereof to be deflected outwardly and obliquely to the axis of rotation, as indicated by the arrows x in Fig. 5, and toward the position shown in dotted lines in that figure, thereby causing the contact-controlling button g to be moved from the position shown in full lines toward the position shown in dotted lines, thus opening the circuit and slowing down the motor. Deceleration of the shaft from any acquired speed will cause the parts to react in the opposite direction, as will be readily understood.

Thus the inertia effect of this governor is combined with its normal centrifugal effect to provide an improved governor of the make-and-break type which is extremely sensitive to variations in speed and which, therefore, is capable of more nearly maintaining constant any desired speed of rotation than prior devices of this nature.

In the drawing, the thickness of the metal forming the bowed spring members *b* and *d* is necessarily shown exaggerated. In practice the metal may be in the neighborhood of from .005 to .008 inch in thickness. Likewise the weights 25 have been shown as being relatively small. It is to be understood that the thickness of the metal of the members *b* and *d* and the weight of the members 25 may be varied as may be required to obtain any desired working condition.

Having thus set forth the nature of the invention, what I claim herein is:

1. A governor for an electric motor having a rotary shaft, comprising a make-and-break switch controlling the flow of electric current to the motor, a pair of resilient and oppositely bowed supporting and connecting elements rotatable with said shaft and rigidly secured together adjacent their ends, said supporting element including portions extending oppositely from said shaft and twisted approximately sixty degrees to the axis of said shaft, weights secured to the connected ends of said resilient elements, and a switch-actuating member carried by said connecting element substantially in line with the axis of said shaft.

2. A governor for an electric motor having a rotary shaft, comprising a make-and-break switch controlling the flow of electric current to the motor, a supporting element carried by said shaft and having oppositely extending arms, each arm having a portion arranged oblique to the axis of the shaft, a deformable connecting element secured at its outer ends to the obliquely arranged portions of said arms, weights secured to said connecting element and arms at their points of connection, and a switch-actuating element carried by said connecting element substantially in line with the axis of said shaft, the outer ends of said arms being arranged to have circumferential and radial components of motion transversely of the axis of said shaft under inertia forces exerted by said weights when the speed of rotation of said shaft is varied, thereby to deform said connecting element to effect actuation of said switch.

3. A governor for an electric motor having a rotary shaft, comprising a make-and-break switch controlling the flow of electric current to the motor, a supporting element carried by said shaft and having arms extending oppositely from the shaft, weights carried at the outer ends of said arms, the outer ends of said arms being constructed and arranged to have a radial component of motion under the centrifugal force of said weights and combined circumferential and radial components of motion obliquely of the axis of the shaft under inertia forces exerted on said arms by said weights during speed changes of said shaft, a bowed connecting element having its opposite ends connected with the outer ends of said

arms and being adapted to be deflected by the movements of said arms under the combined centrifugal and inertia forces, and a switch-controlling element carried by said connecting element substantially in line with the axis of said shaft.

4. A governor for an electric motor having a rotary shaft, comprising a make-and-break switch controlling the flow of electric current to the motor, a bowed-spring supporting element secured to said shaft and having oppositely projecting arms which are twisted in opposite directions to cause their outer ends to lie at an angle of approximately sixty degrees to the axis of said shaft and sixty degrees to each other, a bowed-spring connecting element having its opposite ends connected to the oppositely twisted ends of said arms, weights secured to the connected ends of said arms and connecting element, and a switch-actuating button carried by said connecting element substantially in line with the axis of said shaft, said twisted arms being subject to the centrifugal force exerted by said weights during rotation of said shaft and to the inertia forces of said weights under variation of the speed of rotation, said forces acting on said arms to distort them circumferentially and radially of said shaft thereby to deflect said connecting element and shift said switch-actuating button.

5. A governor for an electric motor having a rotary shaft, comprising a make-and-break switch for controlling the flow of electric current to the motor, a supporting element carried by and rotatable with said shaft and having oppositely extending arms, a pair of weights carried by the outer ends of said arms, a deformable connecting element secured to the outer ends of said arms, a switch-actuating member carried by said connecting element substantially in line with the axis 40 of the shaft, and means embodied in said supporting element to cause the free ends of said arms to be moved circumferentially and radially of said shaft under the inertia of said weights during variation in the speed of rotation of said shaft thereby to deform said connecting element and cause it to actuate said switch.

6. In a motor speed governor, in combination, a rotary shaft, a pair of oppositely and radially disposed governor arms carried by said shaft, governor weights carried at the outer ends of said arms, the outer ends of said arms and said weights being so constructed and arranged that, under inertia forces, the weights will move in paths transversely of a plane containing the axis 55 of said shaft and toward and from said axis, and a diametral switch-operator connected to said weights.

7. A switch actuating element for a speed governor for an electric motor having a rotary shaft, comprising a pair of oppositely and radially disposed arms carried by said shaft, governor weights carried at the outer ends of said arms, means associated with said arms and actuated by the inertia of said weights to cause the weights to be moved toward said axis, during acceleration of said shaft and away from said axis during deceleration thereof, and a diametral switch-operator connected to said weights.

JAMES M. NAUL.
